(57) **CLAIM**

The ornamental design for an unbalanced barbell weight, as shown and described.

DESCRIPTION

FIG. 1 is a perspective view of the disclosed invention, an unbalanced barbell weight, showing my new design; FIG. 2 is a top plan view thereof; FIG. 3 is a bottom plan view thereof; and, FIG. 4 is an edge view thereof as seen from all view point relative to the edge of the invention. The broken lines illustrate portions of the unbalanced barbell weight which form no part of the claimed design.
